CLAIM

The ornamental design for a percussive massage device, as shown and described.

DESCRIPTION

FIG. 1 is a top perspective view of a percussive massage device, showing our new design;
FIG. 2 is a right side elevational view, the left side elevational view being a mirror image thereof;
FIG. 3 is a front elevational view;
FIG. 4 is a rear elevational view;
FIG. 5 is a top plan view;
FIG. 6 is a bottom plan view; and,
FIG. 7 is a bottom perspective view.

1 Claim, 5 Drawing Sheets
